ONE GUN COLOR-DOT TUBE WITH DYNAMIC BEAM CONVERGENCE**Russell R. Law, Princeton, N. J., assignor to Radio Corporation of America, a corporation of Delaware**

Application June 1, 1950, Serial No. 165,551

The terminal 15 years of the term of the patent to be granted has been disclaimed

10 Claims. (Cl. 178—5.4)

This invention relates to electron beam-controlling systems. Though not necessarily limited thereto, it has particular reference to control systems for effecting electron beam convergence in multi-color kinescopes.

The problem of controlling the convergence of a plurality of electron beam components at substantially all points in the plane of a target electrode over which they are deflected to scan a predetermined raster is one which frequently is encountered in television image-reproducing systems. The trend toward providing kinescopes with flatter screens has made the problem of achieving beam convergence more severe. In certain types of kinescopes used in color television systems, the particular problem is to effect accurate convergence of a plurality of electron beams, or their equivalents, which are directed toward a target electrode from different angles. The different angles of approach of the electron beams are employed for color selection purposes.

A representative multi-color kinescope of the type in which color selection is effected by the angle of approach of an electron beam forms the subject matter of a copending U. S. application of Alfred N. Goldsmith, Serial No. 762,175 filed July 19, 1947, now Patent No. 2,630,542 issued March 3, 1953 and titled "Multicolor Television." The Goldsmith tube has a luminescent screen consisting of a multiplicity of phosphor areas of sub-elemental dimensions. The phosphor areas are capable respectively of producing light of different colors when excited by electron beam components. The different screen areas are scanned by electron beams produced by a plurality of guns and projected toward the screen through an apertured masking electrode. The desired color producing phosphor areas are selected by the angle at which the electron beams traverse the apertures of the masking electrode.

Another multi-color kinescope with which the present invention may be employed successfully forms the subject matter of a copending U. S. application of Russell R. Law, Serial No. 165,552, filed June 1, 1950 and titled "Color Television." The Law tube has luminescent screen and masking electrode structure similar to that embodied in the Goldsmith tube. It also operates on generally the same principles. The chief difference is in the provision of only a single electron gun. The electron beam produced by this gun is caused to approach the masking electrode and the luminescent screen from different angles by imparting a spinning type of movement to the beam. By such means the electron beam is caused to rotate about the center or longitudinal axis of the tube so that, at successive intervals, it occupies substantially the same positions as those occupied by the separate electron beams in the Goldsmith tube.

The expression "electron beam components" as used in this specification is intended to cover the type of phosphor-exciting electronic energy produced by a single or a plurality of electron gun. This energy may be continuous or pulsating as required without departing from the scope of this invention.

2

It is necessary for the successful operation of multi-color kinescopes of the type represented by the Goldsmith and Law tubes referred to that the plurality of electron beam components be made to converge substantially in the plane of the masking electrode at all points in the raster or other predetermined pattern scanned thereon by the deflection of the beam components. In order to accomplish this, it is necessary to provide a dynamic convergence control of the electron beam components. One such electron beam control system forms the subject matter of a copending U. S. application of Albert W. Friend, Serial No. 164,444 filed May 26, 1950 and titled "Electron Beam Controlling System." In this Friend application there is provided an electron-optical system which is variably energized as a function of both the horizontal and vertical deflections of the electron beam components. Further details of dynamic beam convergence system may be found in a paper titled "Deflection and Convergence in Color Kinescopes" by A. W. Friend, published in the Proceedings of the I. R. E., vol. 39, No. 10 at page 1249. The present invention is in the nature of an improvement upon the Friend system, particularly in color television systems of a particular character.

The present invention is particularly adapted for use with a color kinescope embodied in a color television system operating in accordance with the dot or elemental multiplex principle. A system of such a character forms the subject matter of a copending U. S. application of John Evans, Serial No. 111,384, filed August 20, 1949 and titled "Color Television." In this type of system, the color information from each elemental area of the television subject is transmitted by successive video signals. The composite video signal wave which includes all of the color information from all of the elemental areas in succession of an image to be reproduced is sampled at a receiving point. The rate at which the video signal sampling is effected is equal to a multiple of the rate at which the elemental areas of the image are to be reproduced. The particular multiple depends upon the number of component colors in which the image is to be reproduced. Ordinarily color television systems employ three component colors. In this case the video signal wave is sampled at the third harmonic of the elemental area repetition frequency.

It is an object of the present invention to provide an improved electron beam control system by which to effect convergence of a plurality of electron beam components substantially at all points in the plane of a target electrode.

Another object of the invention is to provide an improved beam control system for a multi-color kinescope used in a color television system operating according to the elemental multiple principle.

Still another object of the invention is to provide an improved electron beam control system for a multi-color kinescope embodying a single electron gun for selectively exciting a multi-color phosphor screen.

The invention is embodied in an electron-optical system for effecting convergence of a plurality of electron beam components. The system is energized variably in accordance with the deflection of the beam components. The energization of the system also is varied at a frequency substantially higher than the horizontal deflection frequency. Preferably, this higher frequency corresponds to the elemental image area repetition frequency. In a color television system, it may be equal to the frequency at which a composite multiplex video signal wave is sampled.

The novel features that are considered characteristic of this invention are set forth with particularity in the appended claims. The invention itself, however, both as to its organization and method of operation as well

as additional objects and advantages thereof will best be understood from the following description taken in connection with the accompanying drawings.

In the drawings:

Figure 1 is a circuit diagram mostly in block form of a color television signal receiver and image-reproducing system embodying the invention;

Figure 2 is a sectional view of a portion of a color kinescope used in the system of Figure 1, taken on the lines 2-2 of Figure 1. The present figure shows the general configuration and relative positioning of the components of the electron-optical system for effecting dynamic electron beam convergence;

Figures 3, 4, and 5 are views of the kinescope screen;

Figure 3 indicates the non-convergence of the electron beam components in the absence of any dynamic convergence control;

Figure 4 indicates a first order improvement of electron beam convergence by providing dynamic beam convergence control varying as a function of horizontal and vertical beam deflections; and

Figure 5 illustrates a second order improvement of electron beam convergence in which the dynamic convergence control system is varied further as a function of the video signal wave sampling frequency in accordance with this invention.

Reference first will be made to Figure 1 of the drawings. The television signal-receiving or image-reproducing system shown in block diagram form generally is conventional. An antenna 11 is coupled to a composite color television signal receiver 12. It will be understood that this receiver may include the usual carrier wave amplifiers, frequency converter and signal detector. The composite color video signal wave produced by the receiver 12 is impressed upon the video signal channel 13. In a similar manner the received television signal is impressed upon a synchronizing signal separator 14. This apparatus also may be entirely conventional. Accordingly, it will be understood that it includes apparatus for separating the synchronizing signals from the video signals. Also, the horizontal synchronizing signals are separated from the vertical synchronizing signals.

The image-reproducing apparatus also includes a kinescope 15 which, for illustrative purposes, is of the kind disclosed in the copending Law application referred to. Such a kinescope also is disclosed in a paper titled "A One-Gun Shadow-Mask Color Kinescope" by R. R. Law, published in the Proceedings of the I. R. E., vol. 39, No. 10, October 1951 at page 1194. Essentially, it includes a luminescent screen 16, an apertured masking electrode 17 and an electron gun 18. The luminescent screen 16 may be formed on a substantially flat transparent plate. The phosphors are disposed on the inside surface of the plate in any desired pattern. Preferably, multi-colored phosphors are in the form of sub-elemental areas or dots arranged in groups. Each group of phosphor dots contains at least one each of phosphors capable of respectively producing light of the component image colors. The masking electrode 17 is provided with a multiplicity of apertures. These apertures are provided in the same pattern as the groups of phosphor dots appearing upon the screen 16. Each aperture of the electrode 17 is in registration with one group of phosphor dots.

The kinescope 15 also is provided with a deflecting yoke 19 of substantially conventional form. It will be understood that the yoke, when suitably energized, functions to deflect the electron beam components over the masking electrode surface in accordance with a predetermined pattern or raster.

In this case, the plurality of electron beam components is derived from a single electron gun 18. This gun is mounted in such a manner that the electron beam emanating therefrom is substantially along the central longitudinal axis of the kinescope. The electron beam is

subjected to the influence of a rotating field produced by a coil 21 surrounding the neck of the tube substantially as shown. This coil is energized by a constantly changing voltage of a character to produce a rotating field by means of which the electron beam is caused to spin or rotate about the central longitudinal axis. Such apparatus is of the same general type as that shown in Patent 2,057,773 issued October 20, 1936 to W. G. H. Finch.

The kinescope 15 also is provided with a magnetic convergence coil 22. This coil is energized to produce a steady or static field of a character to cause the spinning electron beam to impinge upon a point of the masking electrode 18 located substantially at the center thereof in the absence of any energization of the deflecting yoke 19. Such a coil is of the same general character as a beam focusing coil, an example of which is disclosed in Patent 2,442,975 issued June 8, 1948 to G. L. Grundmann. The magnetic convergence coil 22 is energized from a power source indicated by a battery 23 through a rheostat 24. By suitable adjustment of the rheostat the spinning electron beam may be made to impinge upon the center of the masking electrode 17, irrespective of its radial location relative to the central axis of the tube.

The color kinescope 15 also is provided with an electron-optical system by which to effect convergence of the electron beam components at substantially all points in the raster scanned in the plane of the masking electrode 17. As disclosed herein for illustrative purposes, the electron-optical system comprises a vertical dynamic convergence coil 25 and a horizontal dynamic convergence coil 26. The shape of each of these two coils is generally elliptical so as to provide substantially elliptical or cylindrical electron lenses. Further details of such coils may be found in the Friend I. R. E. paper previously referred to, particularly in the description of Figure 21 of that paper.

The control circuits for the color kinescope 15 also includes the usual deflection generators 27 coupled for control to the synchronizing signal separator 14. The output of the deflection generator, which will be understood to produce substantially sawtooth waves at horizontal or vertical frequencies respectively, is coupled to the deflecting yoke 19. In this manner the deflecting fields produced by the yoke cause the electron beam components to scan the target electrode structure in a predetermined pattern.

The sampling of the composite video signal wave as disclosed herein is in accordance with the so-called high level sampling principle. A system of such signal sampling forms the subject matter of a copending U. S. application of George C. Sziklai, Serial No. 145,420, filed February 21, 1950, and titled "Color Television Receiving System." A high level video signal sampling system consists generally of a single video signal amplifier channel in which the video signals representing all of the component colors are amplified simultaneously. The amplified composite video signal is impressed upon one of a pair of electron beam intensity control electrodes of the color kinescope. The intensity control electrodes normally are biased relative to one another so that no electron beam is produced. The other intensity control electrode is keyed concurrently with the reception of successive color representative video signals. The keying of the electron gun produces an electron beam. The intensity of the electron beam is controlled in accordance with the amplitude of the video signal wave received at that instant. It, therefore, is seen that it is necessary to key the electron beam of the color kinescope at a frequency corresponding to the repetition frequency of the video signals. In a three-color television system this repetition frequency is three times the frequency at which the successive elemental areas of the image are reproduced.

Accordingly, the present apparatus includes a sampling

frequency oscillator 28 coupled for synchronizing control to the synchronizing signal separator 14. The essential requirements of an oscillator by which to control video signal wave sampling are that it be relatively stable at a frequency equal to the frequency at which the elemental areas of an image are to be reproduced and that it be susceptible of synchronous control from an external source. An oscillator of the character described is disclosed in the book entitled "Wave Forms" published by McGraw Hill Inc., New York, at page 143 with particular reference to figure 4-45. The output of the oscillator 28 is essentially a sine wave at an elemental dot frequency of the television image. The output circuit of the oscillator 28 is coupled to a frequency multiplier 29. In the case of a three-color television system the frequency multiplier increases the fundamental frequency produced by the oscillator by a factor of three. The frequency multiplier is coupled to the electron gun 18 as indicated to control the keying of the electron beam in the manner described. The sampling frequency oscillator 28 also is coupled to a rotating field generator 31. This device is coupled to the magnetic convergence coil 21. It is considered that means for producing constantly rotating magnetic fields are so well known generally, as indicated in said Finch Patent 2,057,773, that it is not necessary to disclose a particular one here in order to completely understand this invention. Accordingly, it will be understood that the generator 31 includes means for producing substantially sinusoidal waves of such a character that, when impressed upon the coil 21, there are produced rotating magnetic fields that are always substantially 180° out of phase with one another.

The electron-optical system including the coils 25 and 26, by which dynamic convergence of electron beam components is effected, is energized as a substantially parabolic function of the horizontal and vertical deflection of electron beam components. Accordingly, the vertical dynamic convergence coil 25 is variably energized by a wave produced by a vertical convergence control wave generator 32. It will be understood that this generator 32 includes suitable wave shaping circuits to produce a wave of suitable form to energize the coil 25 in response to signals derived from the deflection generator 27 at the vertical deflecting frequency. A convergence control wave of substantially parabolic form may be produced by a suitable integration of a sawtooth wave as taught in Patent 2,312,054 issued February 23, 1943, to O. H. Schade. In general, the energization of the coil 25 is a minimum when the electron beam components are directed at points substantially at the center of the vertical scansion of the target electrodes. The energization of the coil 25 increases in suitable polarity as a function of an increase in the angle of deflection of the beam components from the central vertical portion of the raster.

The horizontal dynamic convergence coil 26 also is energized by a wave derived from a horizontal convergence control wave generator 33. This apparatus, except for values of the circuit components, may be substantially similar to the generator 32 and may follow the teachings of said Schade Patent 2,312,054. In this case, however, it is required to produce waves of suitable substantially parabolic shape at the horizontal deflection frequency. The output of the generator 33 is coupled to the control grid 34 of an electron tube 35. This tube functions as a signal-combining stage by which to develop a composite control wave for impression upon the coil 26. The anode of the tube 35 therefor is coupled to one terminal of the coil 26. The other terminal of the coil is connected to the positive terminal of a power supply indicated at +B.

The vertical and horizontal convergence control wave generators 32 and 33 may be of the general type disclosed in greater detail in Figure 20, and related description thereof, of the previously referred to Friend I. R. E. 75

paper. The outputs of these generators may be coupled to the convergence coils as indicated in Figure 1 of the drawings herein.

In accordance with a special feature of the present invention a wave component having the fundamental frequency of the sampling frequency oscillator 28 is combined with the output from the wave generator 33. For this purpose the output of the oscillator 28 is coupled through a phase adjuster 36 to a primary coil 37.

10 A secondary coil 38 is inductively coupled to the coil 37 and is connected between a source of positive voltage and the screen grid 39 of the tube 35. Manipulation of the phase adjuster 36 results in the impression of a voltage component at image dot frequency upon an input electrode of the tube 35 in suitable phase to combine effectively with the wave derived from the generator 36 so that an improved dynamic convergence of the electron beam components may be effected by the coil 26.

A graphic illustration of the effectiveness of the system embodying the present invention as given in the Figures 3, 4 and 5 to which reference now will be made.

In Figure 3 the color kinescope is provided with no dynamic convergence control. The central trace 41 is one which is made by a spinning electron beam of the character described. By suitable adjustment of the rheostat 24 the magnetic convergence coil 22 may be energized to converge the spinning beam to a point 42 at the luminescent screen 16. It may be seen from an inspection of the figure that, as the electron beam is deflected both vertically and horizontally from the central position, the convergence of the beam components is subject to a relatively wide variation. For example, the trace 43 located at one extreme of a horizontal deflection of an electron beam no longer is substantially a point as it is at the center of the raster.

It may be appreciated that a spinning beam following a path such as indicated by the trace 43 will produce a misregistration of the electron beam components with the different color-producing phosphor areas of the screen 16. The failure of the beam components to converge any better than indicated by the trace 43 will result in such a degradation of the reproduced image which can not be tolerated. It may be seen from Figure 3 that the tendency of the beam components to fail to converge is much greater in a horizontal sense than in a vertical one.

45 The electron beam traces at different points of the raster as shown in Figure 4 represents the improved operation of a color kinescope when dynamic convergence control means are provided. The dynamic convergence coils 25 and 26 are energized by waves varying in accordance with horizontal and vertical deflection frequencies. However, no energizing component at the dot repetition or sampling frequency is present in the control wave for the dynamic convergence coils. The conditions to produce the results of Figure 4 may be simulated by impressing a constant potential upon the screen grid 39 of the tube 35 of Figure 1.

Figure 5 represents the added improvement in the dynamic convergence of the electron beam components when the sampling frequency component is included in the control wave for the horizontal convergence coil 26.

60 It will be appreciated that alternatively in accordance with this invention, a sampling frequency component may be introduced in the control wave for the vertical convergence coil 25. Also, it will be understood that the present invention may be used successfully with plural electron gun tubes of the type covered by the Goldsmith application referred to. Furthermore, convergence coils 25 and 26 may be combined into a unitary structure which is not necessarily of elliptical shape without departing from the scope of this invention.

Having thus disclosed the nature of the invention, its scope is set out in the appended claims.

What is claimed is:

1. In a cathode ray tube image reproducing system

wherein a plurality of electron beam components effectively traversing paths spaced, respectively, about a longitudinal axis of the tube are deflected horizontally and vertically through substantially equal angles to scan a raster in a predetermined plane, said beam components being differently deflected at any instant by reason of said traversal of spaced paths, a dynamic convergence system to effect convergence of said beam components at all points in said raster comprising, field-producing means disposed adjacent to the paths of said beam components for producing a field of such character as to converge said beam components, means including a source of a substantially parabolic wave for energizing said field-producing means in accordance with the angular deflection of said beam components, and means effectively modifying said substantially parabolic wave for varying the energization of said field-producing means at a frequency higher than that of said horizontal beam deflection.

2. A dynamic electron beam convergence system defined in claim 1 in which said field-producing means includes an electromagnetic coil system for producing both horizontal and vertical field components and said energization varying means is of such a character that it operates to vary the energization of said field-producing means substantially at the elemental image area repetition frequency.

3. A dynamic electron beam convergence system as defined in claim 2 in which, said energizing means is of such a character that it provides energy to vary the horizontal convergence field component at the horizontal beam deflection frequency, and also energy to vary the vertical field component at the vertical beam deflection frequency.

4. A dynamic electron beam convergence system as defined in claim 3 in which, said energization varying means is of such character that it effectively varies only one of said field components.

5. A dynamic electron beam convergence system as defined in claim 4 in which, said energization varying means is of such a character that it effectively varies said horizontal field component.

6. In a color television system, a color kinescope having a luminescent screen comprising a multiplicity of groups of phosphor dots capable respectively of producing light of different component colors of an image when impinged by electrons, an apertured masking electrode spaced behind said screen, said masking electrode having an aperture for, and in substantial registration with, each of said groups of phosphor dots, means for directing toward said screen a video signal-modulated electron beam, means for rotating said beam about a longitudinal axis of said kinescope at a predetermined color cycle repetition frequency, whereby to cause components of said beam to approach said screen from different angles at successive instants in each color cycle, means for angularly deflecting said beam to trace a raster at said screen, said beam components being differently deflected by reason of said beam rotation, a dynamic convergence system adjacent to the path of said rotating beam and energizable to effect convergence of said beam components at all points of said raster, means including a source of a substantially parabolic wave for varying the energization of said convergence system proportional to the angular deflection of said beam components, and means effectively modifying said substantially parabolic wave for varying the energization of said convergence system proportional to said color cycle repetition frequency.

7. In a color television system, a color kinescope having a luminescent screen comprising a multiplicity of groups of phosphor dots capable respectively of producing light of different component colors of an image when impinged by electrons, an apertured masking electrode spaced behind said screen, said masking electrode having an aperture for, and in substantial registration with, each of said groups of phosphor dots, means for directing

5 toward said screen a video signal-modulated electron beam, means for rotating said beam about a longitudinal axis of said kinescope at a predetermined color cycle repetition frequency, whereby to cause components of said beam to approach said screen through said masking electrode from different angles at successive instants in each color cycle, means for deflecting said beam horizontally and vertically to trace a raster at said screen, said beam components being differently deflected by reason of said beam rotation, a dynamic electromagnetic convergence system surrounding the path of said rotating beam and energizable to effect convergence of said beam components at all points of said raster, means including a source of a substantially parabolic wave for varying the energization of said convergence system at a rate proportional to the vertical deflection frequency, means including a source of a substantially parabolic wave for varying the energization of said convergence system at a rate proportional to the horizontal deflection frequency, and

10 means effectively modifying one of said substantially parabolic waves for varying the energization of said convergence system at a rate proportional to said color cycle repetition frequency.

20 8. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

25 means effectively modifying one of said substantially parabolic waves for varying the energization of said convergence system at a rate proportional to said color cycle repetition frequency.

9. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

30 means effectively modifying one of said substantially parabolic waves for varying the energization of said convergence system at a rate proportional to said color cycle repetition frequency.

35 10. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

40 means effectively modifying one of said substantially parabolic waves for varying the energization of said convergence system at a rate proportional to said color cycle repetition frequency.

45 11. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

50 means effectively modifying one of said substantially parabolic waves for varying the energization of said convergence system at a rate proportional to said color cycle repetition frequency.

55 12. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

60 means effectively modifying one of said substantially parabolic waves for varying the energization of said convergence system at a rate proportional to said color cycle repetition frequency.

65 13. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

70 means effectively modifying one of said substantially parabolic waves for varying the energization of said convergence system at a rate proportional to said color cycle repetition frequency.

75 14. In a color television system, a color kinescope having a luminescent screen comprising a multiplicity of groups of phosphor dots capable respectively of producing light of different component colors of an image when impinged by electrons, an apertured masking electrode having an aperture for, and in substantial registration with, each of said groups of phosphor dots, means including an electron gun for directing toward said screen a video signal-modulated electron beam, means for rotating said beam about a longitudinal axis of said kinescope at a rate proportional to the vertical deflection frequency, means including a source of a substantially parabolic wave for varying the energization of said convergence system at a rate proportional to the horizontal deflection frequency, and

said beam components at all points of said raster, means including a first substantially parabolic wave generator for variably energizing said vertical coil at said vertical deflection frequency, means including a second substantially parabolic wave generator for variably energizing said horizontal coil at said horizontal deflection frequency, and means effectively modifying said substantially parabolic wave at horizontal deflection frequency for variably energizing said horizontal coil at said color cycle repetition frequency.

10. In a color television system, a color kinescope having a luminescent screen comprising a multiplicity of groups of phosphor dots capable respectively of producing light of different component colors of an image when impinged by electrons, a masking electrode spaced behind said screen and having an aperture for and in register with each of said groups of phosphor dots, means including an electron gun for directing toward said screen a video signal-modulated electron beam, means including a rotating field-producing system for rotating said beam about the central longitudinal axis of said kinescope at a predetermined color cycle repetition frequency, whereby to cause components of said beam to approach said screen through successive ones of said apertures from different angles at successive instants in each color cycle, means for deflecting said beam horizontally and vertically at different frequencies to trace a raster at said screen, said beam components being differently deflected by reason of said beam rotation, horizontal and vertical dynamic convergence coils surrounding the path of said rotating

beam and energizable to effect convergence of said beam components at all points of said raster, means including a vertical frequency substantially parabolic wave generator for variably energizing said vertical coil, means including a horizontal frequency substantially parabolic wave generator for variably energizing said horizontal coil, and means including an oscillator producing a substantially sinusoidal wave having said color cycle repetition frequency for variably energizing said horizontal coil.
